UNITED STATES PATENT OFFICE

135,281

DESIGN FOR AN ADVERTISING SIGN OR THE LIKE

Milton M. Gair, Redlands, Calif.

Application December 28, 1942, Serial No. 109,153

Term of patent 14 years

To all whom it may concern:

Be it known that I, Milton M. Gair, a citizen of the United States of America, residing at Redlands, in the county of San Bernardino and State of California, have invented a new, original, and ornamental Design for an Advertising Sign or the like, of which the following is a specification, reference being had to the accompanying drawing, forming a part thereof.

Fig. 1 is a perspective view of an advertising sign, showing my new design; and

Fig. 2 is an enlarged section on the line 2—2 of Fig. 1.

I claim:

The ornamental design for an advertising sign or the like, substantially as shown.

MILTON M. GAIR.
